ELECTRIC BELL

Gwyn O. O. Davies, Cle Elum, Wash.

Application May 16, 1929. Serial No. 363,608

3 Claims. (Cl. 177—7)

This invention relates to electric bells.

It is one of the objects of the present invention to provide a novel and improved bell which will be simple and efficient in construction and operation, and which will materially reduce the electrical energy used in the normal operation of electric bells.

A further object of the present invention is to provide a bell operating structure in which the 10 clapper arm of the bell and the armature of the associate electro-magnet are separate and distinct units.

A further object of the present invention is to provide an armature and a clapper arm assembly whereby movements of the armature and clapper arm will control periodic energization of their associated magnets, and whereby the frequency of the bell operation may be readily adjusted for any desired frequency.

20 A further object of the present invention is to provide an electrical bell operating structure by means of which the period of energization of the electromagnet of the assembly will be of less duration than in the conventional operating structure now in use.

A further object of the invention is to provide in a device of the character described, a clapper arm controlled circuit controller arranged to provide a wiping contact whereby the contact surface 30 faces will be self-cleaning.

A still further object of the present invention is to provide a bell operating structure in which the armature is arranged to move in close proximity to the poles of its associated electromagnets, whereby the reluctance of the electromagnetic path will be reduced, thus increasing the efficiency of the structure.

Other important objects of the present invention include the combination and interrelation 40 of parts whereby the whole forms a novel and simple construction, highly efficient in operation and well designed to meet the demands of economic manufacture.

Numerous other objects and features of the 45 present invention will be apparent from a consideration of the following specification taken in conjunction with the accompanying drawing, in which

Figure 1 is a side elevation of one form of the 50 bell operating structure embodying the present invention;

Fig. 2 is a detailed view showing the relationship of the armature and clapper arm while the circuit is completed therethrough; and

55 Fig. 3 is a view similar to Fig. 2, showing the

relationship of the clapper arm and armature with the circuit broken therethrough.

Referring more particularly to that form of the invention illustrated in Fig. 1 of the accompanying drawing, it will be understood that the 60 embodiment of the invention here presented is one form only and that the invention is not confined to the specific structural features as herein illustrated.

In Fig. 1 of the drawing the bell has been indicated by the numeral 10 and may, of course, be of any conventional shape or design. Associated with the bell 10 is a clapper or hammer 11 mounted upon the extremity of a clapper arm 12, which is pivotally mounted to a suitable supporting 70 base, not shown.

Adjacent the pivot point of the clapper arm 12 an angularly extending conducting crank arm 13 is provided, the extremity of which is positioned adjacent the armature 14, the extremity of the 75 armature being provided with a pair of rounded segments 15 and 16. Segment 15 is formed of conducting material electrically connected with the conducting arm 13, while segment 16 is formed of insulating material.

The armature 14 is pivoted to the base by the pivot 17, the armature being retained in spaced relation to its associated magnets by a spring 18. A flexible conductor 19 associated with the armature 14 is provided which extends to one of a pair 85 of binding posts 20. The other binding post 20 is associated by a conductor 21 with a pair of electromagnetic coils 22, the other side of which is electrically connected with the crank 13 by a suitable conductor 23. The conductor 23 is preferably flexible and is fastened as near the pivotal point of the clapper arm as possible, thus to reduce the amount of its motion.

For controlling the length of the inward movement towards the magnets of the armature 14, a 95 readily adjustable stop screw 24 is provided, and adjacent the stop screw the armature 14 is associated with an adjustable spring assembly 25 which provides for assisting the spring 18 and damping the vibration of the armature 14. 100

In the operation of the device as herein presented, it is understood that associated with the binding posts 20 a suitable source of potential and a circuit controller therefor is provided, the arrangement being such that when the circuit controller completes the circuit of potential will be applied across the binding posts 20.

The normal position of rest of the device is as shown in Figs. 1 and 2. When in such position, and when the potential is applied across the bind- 110

ing posts 20, the current will pass through the conductor 19, through the armature 14, and through segment 15 to the crank 13, and thus through the conductor 23 to energize the electromagnets 22. 5 The circuit being completed through the conductor 21 to the opposite binding post 20, the electromagnets will be energized and the armature 14 will be pivotally moved in a counter-clockwise direction as shown in Fig. 1, against the tension of the spring 18, thus forcing upwardly the clapper 11 for contact with the bell 10, the spring 25 acting as a damper of the return motion of the armature.

In such movement the relation of the segments to the armature 14 and the crank 13 will be as shown in Fig. 3. In such movement it will be noted that the segments move arcuately with respect to the crank 13 whereby the insulated segment 16 is the engaging portion of the armature 14 with respect to the crank 13. Thus the circuit 15 between the armature 14 and the crank 13 will be broken and the electromagnets will become dis- 20 energized, and under the influence of the spring 18 the armature will resume the position shown in Fig. 1, thus re-energizing the magnets and providing for periodic energization thereof.

It is important to note in connection with the present invention that only slight inward movement of the armature 14 will be sufficient to break the contact between the segment 15 and the crank 13. Thus the period of energization of the magnets is considerably less than will be found in conventional bells now in use. A great saving of current results from the fact that the armature is permitted to return to its position of rest immediately allowing the clapper member to travel a considerable distance to the bell and permitting it to deliver a hammer-like blow, being entirely free from the influence of the armature retention springs, which in present type bells must be fairly strong in order to secure good electrical connection for the contacts. During this return travel of the armature no current is flowing in the circuit. Also there is no current flowing during the return motion of the clapper arm. The current thus saved is considerable.

It will be noted further that when the striking impulse has been delivered to the clapper arm it is free to move to strike the bell regardless of the outward movement of the armature 14 directly upon the cessation of the energization of the magnets 22.

It will be noted that the bell will function properly without insulation segment 16. The segment is recommended in bells intended for very important service or bells designed to withstand heavy vibration, such as street car bells, etc. The object of this insulation is to prevent the clapper assembly from locking. For example, suppose a vibration forced the clapper arm and crank back against the armature before it had returned to its rest position. The clapper having no momentum would rest against the contact 15, the coils being energized would hold the armature, the current would continue to flow, but ringing would have ceased. However, when stop screw 24 is adjusted properly, no current flows even if clapper assembly is held against it. Therefore, as soon as this restraining force releases clapper member the ringing cycle will resume. In cheap bells this refinement is not necessary.

The invention thus provides for improved efficiency in view of the fact that the energization period or power-consuming period of the magnet is greatly diminished without diminishing the effectiveness of the device.

It will further be seen that the present invention provides ready means for controlling the frequency of the periodic contact of the clapper 11 with the bell 10. It will be seen that by adjusting the spring 25 and the stop screw 24, or by adjusting the angular relation of the clapper arm or its length, the period of energization and the frequency of energization may be readily controlled, thus controlling not only the time factor involved, but also, controlling the rate at which the bell is struck.

From the foregoing it will readily be seen that the present invention provides a novel, simple and improved construction which will be highly efficient in operation and well designed to meet the demands of economic manufacture. It will be understood, furthermore, that numerous changes and modifications, together with the full use of equivalents, may be resorted to in the accomplishment of the present invention, without departing from the spirit or scope of the appended claims.

I claim:

1. In a device of the class described, a bell, a pivoted arm with a clapper disposed adjacent the bell for striking the latter and having a contact operating member, an electro-magnet, a pivoted armature movable under the influence of the magnet, a spring tending to move the armature away from the electro-magnet, the armature extending in the direction of the contact operating member and being disposed adjacent a side of the latter, the armature having a contacting surface normally engaging the contact operating member, the said contacting surface consisting of a conducting member and an insulating member, with the conducting member disposed between the insulating member and the armature pivot, so that the conducting member will engage the contact operating member when the armature is in non-actuated position and the conducting member will be out of engagement with the insulating member will be disposed for engagement with the contact operating member when the armature is in actuated position, and a circuit through the armature conducting member, the contact operating member and the electro-magnet.

2. In a device of the class described, a bell, means for operating the bell, the said means having a contact operating member, an electro-magnet, a pivoted armature movable under the influence of the magnet, a spring tending to move the armature away from the electro-magnet, the armature extending in the direction of the contact operating member and being disposed adjacent a side of the latter, the armature having a contacting surface normally engaging the contact operating member, the said contacting surface consisting of a conducting member and an insulating member, with the conducting member disposed between the insulating member and the armature pivot, so that the conducting member will engage the contact operating member when the armature is in non-actuated position and the conducting member will be out of engagement with the insulating member will be disposed for engagement with the contact operating member when the armature is in actuated position, and a circuit through the armature conducting member, the contact operating member and the electro-magnet.

3. In a device of the class described, a bell, a pivoted arm with a clapper disposed adjacent the bell for striking the latter and having a contact operating member, an electro-magnet, a pivoted

armature movable under the influence of the magnet, the armature extending in the direction of the contact operating member and being disposed adjacent a side of the latter, the armature 5 having a contacting surface normally engaging the contact operating member, the said contacting surface consisting of a conducting member and an insulating member, with the conducting member disposed between the insulating member 10 and the armature pivot, so that the conducting member will engage the contact operating member when the armature is in non-actuated posi-
tion and the conducting member will be out of engagement with and the insulating member will be disposed for engagement with the contact operating member when the armature is in actuated position, a circuit through the armature conducting member, the contact operating member and the electro-magnet, means to limit the movement of the armature in one direction, and resilient means for moving the armature yieldingly in the opposite direction.
